UNITED STATES PATENT OFFICE

2,361,550

GRINDING MACHINE

Edward C. Krueger, Otsego, Mich., assignor to
Hammond Machinery Builders, Inc., Kalamazoo, Mich., a corporation of Michigan

Application February 3, 1944, Serial No. 520,883

13 Claims. (Cl. 51—272)

This invention relates to improvements in grinding machines.

The main objects of this invention are:

First, to provide a structure in which a grinding wheel of the annular cup or cylinder type, as such wheels are interchangeably designated, is effectively guarded to protect the operator and the tools or work being ground.

Second, to provide in a grinder of this type a guard which is automatically adjusted with the wheel housing as the wheel housing is adjusted to accommodate any grinding wheel and as the wheel housing is adjusted to compensate for wear of the grinding wheel.

Third, to provide a structure embodying these advantages which while efficient and effective is very economical.

Objects relating to details and economies of the invention will appear from the description to follow. The invention is defined in the claims.

Preferred embodiments of the invention are illustrated in the accompanying drawing, in which:

Fig. 1 is a fragmentary front perspective view of a grinding machine embodying the features of my invention.

Fig. 2 is an enlarged fragmentary view partially in section on the broken line 2—2 of Fig. 3.

Fig. 3 is a fragmentary front elevation illustrating details and the relationship of certain of the guard parts to the grinding wheel.

Fig. 4 is a fragmentary vertical section illustrating a slightly modified form or embodiment of my invention and further illustrating the adjustment of the guard relative to the grinding wheel.

In the accompanying drawing, 1 designates generally a grinding machine of the type in which I have embodied my invention, this grinding machine comprising a grinding wheel 2 of the annular or cup or cylinder type, the wheel being provided with a sheet metal web 3 detachably secured by screws 4 to the head 5 on the shaft or spindle 6.

The wheel hood or the housing 7 is mounted to telescope within the frame 8 of the machine as is illustrated in Figs. 1 and 2, this housing being carried by the adjustable carriage 9, the adjusting screw thereof being indicated at 10. The table 11 is mounted on the carriage for adjustment relative to the grinding wheel, the adjusting means being generally indicated at 12.

The wheel housing 7 has a front wall or apron 13 depending in front of the grinding wheel and covering the upper portion thereof. On the in-

ner side of this front wall 13 I mount a guard disk 14, this disk being supported by means of the screws 15 and the spacing blocks 16, see Fig. 2, so that the disk lies within the grinding wheel with its edges adjacent to but peripherally spaced from the inner wall of the inner periphery of the grinding wheel as is clearly shown in Figs. 2, 3 and 4. By thus mounting the guard disk, it does not interfere with the presentation of work to the grinding wheel but it is effective in preventing an operator from inserting his hands or tool into the grinding wheel, and the work table 11 is so associated therewith that the work is effectively guarded which not only results in the protection of the work and the operator but also of the grinding wheel.

I also preferably embody in this combination a splash guard and tool guard of the type generally illustrated in my Patent 2,292,229, issued

August 4, 1942.

In this embodiment, the guard or shield comprises an arcuate portion 17 disposed axially of the grinding wheel and an arcuate flange-like portion 18 disposed radially on the inner side of the depending front wall 13. The inner edge of this arcuate portion 18 constitutes a track which engages the rollers 19 whereby the shield is oscillatingly supported, the handle 20 for effecting this adjustment being pivoted on the depending bracket 21 and projecting through the slot 22 on the bracket or hanger.

In the embodiment shown in Fig. 4, the shield is carried by an arm 23 which is directly pivoted on the bracket 24, the hand-piece 25 being secured to this arm. In this embodiment, the guard 26 corresponding to the guard 14 is secured to the bracket 27 corresponding to the bracket 21 by the screw 28. The guard 26 is, in this embodiment, supported in alignment with the axis of the wheel instead of at one side thereof as is shown in the embodiment of Figs. 1 to 3. However, the general relationship of the parts is the same.

In Fig. 4, I illustrate a grinding wheel that is substantially worn away and this in comparison with Fig. 2 illustrates the manner in which the guard is adjusted relative to the grinding wheel. It bears the same relation to the grinding wheel in all positions of adjustment. Even careless use or manipulation is guarded against as, for example, in the event the workman did not adjust the wheel hood or housing in proper relationship to the wear on the wheel at the proper time, that is, in the event he permitted too much wear to occur before adjustment this would be evidenced

by the relationship of the work supporting table to the wheel.

In the embodiment of my invention illustrated, the skirt or lower portion of splash guard 17 terminates in a rearwardly inclined bottom edge 171 offset inwardly at 172 providing a drip or flow directing semi-trough. The fluid is effectively directed away from the work and work table which is of substantial advantage.

I have illustrated and described my invention in very practical commercial embodiments thereof. I have not attempted to illustrate or described certain other embodiments or adaptations which I contemplate as it is believed that this disclosure will enable those skilled in the art to effectively adapt or embody my invention to different types of structures of grinding machines employing annular grinding wheels. Further, I have illustrated and described only such portions of a grinding machine as seem to me to be desirable for a full understanding of my invention and practical adaptations thereof.

Having thus described my invention, what I claim as new and desire to secure by Letters Patent, is:

1. In a grinder, the combination with an annular grinding wheel provided with a supporting web at the inner end thereof, of a wheel housing overhanging and mounted for adjustment axially of said grinding wheel and having a front wall depending in front of the upper portion of the grinding wheel, a work table operatively associated with said grinding wheel, a guard disk mounted on the inner side of said wheel housing front wall and positioned within said annular grinding wheel with its edges closely adjacent to but spaced from the inside thereof, an arcuate shield disposed within said housing and comprising an arcuate axially projecting flange portion and a radial flange disposed between the front wall of said housing and said guard disk and supported on said front wall for angular adjustment within the housing and for adjustment relative to said work table.

2. In a grinder, the combination with an annular grinding wheel provided with a supporting web at the inner end thereof, of a wheel housing overhanging and mounted for adjustment axially of said grinding wheel and having a front wall depending in front of the upper portion of the grinding wheel, a work table operatively associated with said grinding wheel, and a guard disk mounted on the inner side of said wheel housing front wall and positioned within said annular grinding wheel with its edges closely adjacent to but spaced from the inside thereof.

3. In a grinder, the combination with an annular grinding wheel, of a wheel housing overhanging and mounted for adjustment axially of said grinding wheel and having a part depending in front of the upper portion of the grinding wheel, a guard disk mounted on the inner side of said depending part of said wheel housing and positioned within said annular grinding wheel with its edges closely adjacent to but spaced from the inside thereof, an arcuate shield disposed within said housing and comprising an arcuate axially projecting flange portion and a radial flange disposed between the front wall of said housing and said guard disk and supported on said front wall for axial adjustment within the housing.

4. In a grinder, the combination with an annular grinding wheel, of a wheel housing overhanging and mounted for adjustment axially of

said grinding wheel and having a part depending in front of the upper portion of the grinding wheel, and a guard disk mounted on the inner side of said depending part of said wheel housing and positioned within said annular grinding wheel with its edges closely adjacent to but spaced from the inside thereof.

5. In a grinder, the combination with an annular grinding wheel, of a wheel housing mounted for adjustment axially of the wheel and comprising a front wall depending in front of the wheel, and a guard disk mounted on the inner side of said housing to depend below said housing front wall and positioned within said grinding wheel with its edges peripherally adjacent to but spaced therefrom.

6. In a grinder, the combination with an annular grinding wheel, of a wheel housing comprising a portion depending in front of the wheel, and a guard disk mounted on said depending part of said housing and positioned within said grinding wheel with its edges peripherally adjacent to but spaced therefrom.

7. In a grinder, the combination with an annular grinding wheel provided with a supporting web at the inner end thereof, of a wheel housing provided with a part depending in front of said wheel, said wheel housing being mounted for adjustment axially of the wheel, and a guard disk mounted on said depending part of said wheel housing and supported thereby within said grinding wheel adjacent the grinding face thereof and adjustable within said grinding wheel with the axial adjustment of said wheel housing.

8. In a grinder, the combination of an annular grinding wheel, a wheel housing mounted for adjustment axially of said wheel, a guard member mounted on said housing for adjustment therewith and disposed within said grinding wheel, and a work table adjustably associated with said grinding wheel.

9. In a grinder, the combination of an annular grinding wheel, a wheel housing mounted for adjustment axially of said wheel, and a guard member mounted on said housing for adjustment therewith and disposed within said grinding wheel.

10. In a grinder, the combination with an annular grinding wheel, of a wheel housing mounted for adjustment axially of the wheel, and a guard disk mounted on said wheel housing and supported thereby within said grinding wheel adjacent the grinding face thereof and adjustable with said grinding wheel housing.

11. In a grinder, the combination of an annular grinding wheel, a wheel housing, and a guard member mounted on said housing and disposed within said grinding wheel.

12. In a grinder, the combination with an annular grinding wheel, of a wheel housing, and a guard member mounted on said housing and positioned within said grinding wheel with its edges peripherally adjacent to but spaced therefrom.

13. The combination with a reversible fluid supplied grinding wheel, of a wheel housing having openings therein at the opposite sides of the wheel, and a shield comprising a curved portion embracing a substantial portion of the periphery of the grinding wheel and mounted for pivotal adjustment concentrically of the wheel, said shield having a skirt portion terminating in inwardly inclined bottom edges.
